SPHERICAL SURFACE GENERATING DEVICE

Arthur J. Holman, Brighton, N. Y.

Application November 14, 1942, Serial No. 465,605

23 Claims. (Cl. 51—55)

My invention relates to apparatus for generating optical surfaces, and it has been the special object of my invention to make an improved spherical grinding and polishing machine which will possess the essential characteristics of a spherical generator inherent in my former device described in Letters Patent of the United States No. 1,827,748 dated October 20, 1931, and in addition thereto, will have the following advantages: less expensive to construct, easier to operate, better suited for mass production of lenses when operated in batteries, and adaptable for greater range of surface curvatures, particularly in the short radius curves. While retaining substantially all of the spherical surface generating characteristics of my rotating concentric universal joint mechanism, the present device employs only one universal joint and this does not rotate during the operation of the machine. Convex surfaces may be tipped up out of grinding and polishing position for minute inspection with a loupe without removal from the mechanism and, moreover, the entire work spindle with the work mounted thereon may be removed and transferred from machine to machine for progressive grinding and for polishing without the least danger of disturbing the precise adjustment either of the radius of curvature or of the center of oscillation, both of which are supercritical in all lens surface generating apparatus. This apparatus requires less skill and judgment, on the part of the operator, than my former device and it will produce more precision surfaces per hour of operation, particularly when the machines are operated in batteries and the work is advanced from machine to machine in the process of grinding and polishing.

My device may be best understood by reference to the accompanying drawings in which

Fig. 1 is a front view of my device, showing the concave lap in section

Fig. 2 is a side view

Fig. 3 is a top view to somewhat larger scale

Fig. 4 is a vertical section through the axis of hinge pins 7 and 8 on line 4—4 of Fig. 2, to somewhat larger scale

Fig. 5 is a vertical section through the tilting gear boxes on line 5—5 of Fig. 2

Fig. 6 is a vertical section through the tilting gear boxes on line 6—6 of Fig. 5

Fig. 7 is a vertical section through cage member 68 on line 7—7 of Fig. 3

Fig. 8 is a section through the main gear box on line 8—8 of Fig. 3

Fig. 9 is a section through the main gear box on line 9—9 of Fig. 8.

Fig. 10 is a section through tilting bracket 9, as in Fig. 7, showing displacement of axes of oscillation.

Referring now more specifically to the drawings in which like reference numerals indicate like parts, 1 is a base of cast metal (Fig. 1) to which are bolted supporting brackets 2 and 3, these being accurately spaced and squared at their rear ends by cross member 4. These parts, accurately fitted together and doweled, constitute the structural frame work of my device, serving to support the oscillating mechanisms, their driving cranks and associated gear trains.

Supporting brackets 2 and 3 (Fig. 4) have press fitted within bores at their upper extremities bearing metal bushings 5 and 6 respectively, into which are fitted with very slight clearance the hinge pins 7 and 8. The tilting bracket 9 is provided with a bore in each end, which bores are in exact alignment and into these are press fitted the pins 7 and 8. Between tilting bracket 9 and the upper end of supporting bracket 2 is hingedly mounted cage supporting member 10 in the following manner: Into a bore in the upper end of cage supporting member 10 is lightly press fitted the outer race of ball bearing 11, the inner race of which is lightly press fitted on hinge pin 7; an accurately turned projecting boss on tilting bracket 9 fits with slight clearance in the bore in cage supporting member 10 and, on the opposite side of member 10, a bore of reduced diameter fits with slight clearance over a turned projection on bearing metal bushing 5. By means of a spacer washer 12 ground to uniform thickness, a threaded portion 13 on hinge pin 7 and a threaded collar 14 fitting thereon, it is a simple matter to eliminate all lost motion between supporting bracket 2, cage supporting member 10 and the tilting bracket 9. Hinge pin 1 is provided with head 15 to prevent its being withdrawn from tilting bracket 9 when collar 14 is tightened securely. Collar 14 is provided with a set screw 16 to fix its position on hinge pin 7 after all lost motion between the parts has been eliminated. It will be apparent that this construction permits preloading of ball bearing 11 and hence eliminates all end play in this bearing.

In exactly the same manner, cage supporting member 17 containing ball bearing 18 within a bore in its upper end, is retained on hinge pin 8 and in proper relation with tilting bracket 9 and supporting bracket 3 by the threaded collar 19 which is fixed on hinge pin 8 by set screw 20.

This construction permits cage supporting brackets 10 and 17 to swing on hinge pins 7 and 8 respectively, and also permits tilting bracket 9 to swing on its supporting brackets 2 and 3.

Tilting bracket 9 has an integral boss 21 (Figs. 3 and 5) into a bore in which is press fitted supporting pin 22. This bore in boss 21 and the bore in tilting bracket 9 wherein hinge pin 8 is press fitted, are so arranged that supporting pin 22 and hinge pin 8 are exactly parallel as they project from tilting bracket 9. Hinge pin 8, after passing through threaded collar 19, projects through the end wall 23 (Figs. 4 and 5) of gear box 24, wherein it is a light press fit. End portion 25 of hinge pin 8 is of reduced diameter and serves as supporting stud for gears as will be explained hereinafter more fully. On the outboard end of end portion 25 is mounted a collar 26 (Fig. 4) which is pinned to end portion 25 for the purpose hereinafter explained.

A gear box 27 (Figs. 3, 5, and 6) has an integral boss 28 which is bored to a light press fit on supporting pin 22. The lower part 29 of gear box 27 contains a bore of somewhat larger diameter which is concentric with the bore in boss 28. Gear box 27, its integral lower portion 29, and gear box 24 are joined together (Fig. 6) by integral web 30 and by the gear box 31. In fact, all these parts are integral portions of one and the same casting which carries, projecting from its lower portion, the radius arm 32 ending in the boss 33 (Figs. 4, 5, and 6). It will be apparent from the drawings that these integral gear boxes 24, 27, and 31 are supported rigidly from tilting bracket 9 by means of hinge pin 8 and supporting pin 22 and, furthermore, the angular position of tilting bracket 9, with respect to its supporting brackets 2 and 3, is determined by the position of radius arm 32. Any displacement of radius arm 32 from the vertical position will cause tilting bracket 9 and the rigidly attached gear box casting to swing around the axis of hinge pins 7 and 8. Fitted upon the end of gear box 24, with freedom to turn thereon (Fig. 4) is gear box 34 which is held in operating position by the collar 26 previously described.

Projecting through the bore in boss 33 at the lower end of radius arm 32 (Fig. 4) is sleeve 35 having the head portion 36 contacting one face of boss 33. From the other face of boss 33 projects threaded portion 37 of sleeve 35 whereon is screwed the hollow hand grip 38. Within the sleeve 35 is slidably fitted with slight clearance the stop pin 39 having a portion 40 of reduced diameter which passes with slight clearance through a bore in the outer end of hand grip 38. Fixed on the protruding end of portion 40 of stop pin 39 is the release grip 41 (Figs. 5 and 6). A coil spring 42 surrounding portion 40 of stop pin 39 tends to push stop pin 39 into a bore in boss 43 integral with supporting bracket 3, thereby locking tilting bracket 9 in a horizontal position with respect to supporting brackets 2 and 3. Supporting bracket 3 also carries integral boss 44 (Fig. 2) wherein is located a bore like the bore in boss 43 and the same radial distance from hinge pin 8. Whenever it is desired to lock tilting bracket 9 in non-operating position for inspection or removal of the work, as is described fully hereinafter, stop pin 39 entering the bore in boss 44 serves this purpose.

Tilting bracket 9 supports the upper oscillating member 49 in the following manner: A pair of diametrically opposite bosses 45 and 46 (Figs. 3 and 7) on tilting bracket 9 are bored in exact

alignment, the axis of these bores intersecting at right angles the axis of the bores into which hinge pins 7 and 8 are press fitted. The exterior face of each boss 45 and 46 (Fig. 7) is finished square to the bore, and the dimension measured from the axis of hinge pins 7 and 8 to each of these faces is identical. Within the bore in boss 45 is lightly press fitted the outer race of ball bearing 47, the inner race of which is a light press fit on the hinge pin 48, the latter being a good press fit in a bore in upper oscillating member 49. Within the bore in boss 46 is lightly press fitted the outer race of ball bearing 50, the inner race of which is a light press fit on the hinge pin 51, the latter being a good press fit in a bore in upper oscillating member 49. The hinge pins 48 and 51 are in exact alignment and the faces of the bosses on upper oscillating member 49 from which the hinge pins protrude are finished square to the axis of the pins and to the exact same dimension measured from the axis of upper oscillating member 49. The axis of hinge pins 48 and 51 intersects at right angles the axis of the principal bore in upper oscillating member 49. Spacer washers of the same thickness are placed between these faces and the inner races of the ball bearings 47 and 50, and bearing retainer caps 52 and 53, designed to maintain the exact centering of upper oscillating member 49 within the tilting bracket 9, are arranged to preload these bearings. Retaining caps 52 and 53 are attached to bosses 45 and 46 respectively by suitable screws.

Upper oscillating member 49 contains two aligned bores (Fig. 4), one in its lower end and the other in its upper end, and these bores determine the principal axis of this member. Into the lower bore is lightly press fitted the outer race of ball bearing 54, the inner race of which is lightly press fitted on sleeve 55. Into the upper bore is lightly press fitted the outer race of ball bearing 56, the inner race of which is lightly press fitted also on sleeve 55. Sleeve (or hollow spindle) 55 contains a bore exactly concentric with the seats whereon the ball bearings are fitted and it is also provided with a flanged head 57 against which the inner race of ball bearing 54 abuts. Flanged head 57 is relieved adjacent the outer race of this bearing, and its outer periphery is a free running fit within the lower and larger bore in upper oscillating member 49. The upper end of oscillating member 49 is enlarged to form the gear box 58 having a cover 59 retained in position by suitable screws. Worm gear 60 is a snug sliding fit on sleeve 55 and is suitably keyed thereto to prevent rotation on the sleeve. The upper end of sleeve 55 is threaded to fit a threaded sleeve 61 which passes through the gear box cover 59 with a slight clearance for turning. The construction of the upper oscillating member 49 is such that any desired amount of preloading on ball bearings 54 and 56 may be obtained by tightening or backing off threaded sleeve 61. A spindle 62, fitted with just sufficient clearance to slide without binding in the bore in sleeve 55, carries on its lower end the tool 63. Spindle 62 is slotted on one side, and a spring actuated key pin 64, entering the slot, causes spindle 62 and tool 63 to rotate with sleeve 55. The lower end of the slot in spindle 62 is made of sufficient size and depth to allow the end of key pin 64 to enter spindle 62 to a depth somewhat greater than that of the keyway, thereby causing spindle 62 and the tool or work mounted thereon to be locked automatically at the highest position of spindle 62 within the sleeve 55. A worm 65 (Fig. 7) meshes with worm gear 60 and

causes sleeve 55 to rotate when shaft 86, whereon worm gear 65 is mounted, is power actuated as described hereinafter.

The lower oscillating member 68, or cage, is supported from the cage supporting members 10 and 17 in the following manner: A pair of rods 67 (Figs. 1 and 3) are press fitted in bores in integral bosses at the lower end of cage supporting member 10 and a like pair of rods 67 are fixed, in the same manner, in the lower end of cage supporting member 17. The four rods 67 are parallel and they are so positioned that the axis of each rod 67, if extended, will be exactly the same distance from the common axis of hinge pins 7 and 8. A cage member 68 (Figs. 1 and 7) having four corner bosses 69 extending throughout its height, has bores within these bosses laid out exactly according to the geometrical pattern of the arrangement of the rods 67, so that cage member 68 may be variously positioned along rods 67 for adjustment of the radius of oscillation of the lower tool. At the exact center of the geometrical pattern formed by rods 67 and within the body of cage member 68, are two aligned bores, the upper bore having lightly press fitted therein the outer race of ball bearing 70 (Fig. 7), the lower bore having lightly press fitted therein the outer race of ball bearing 71. A sleeve 72 is provided with concentric seats whereon the inner races of ball bearings 70 and 71 are lightly press fitted. Sleeve (or hollow spindle) 72 has a flanged head against which tool 73 seats when it is screwed into position in the threaded bore in the upper end of sleeve 72. A sealing ring 74, fixed on the flanged head of sleeve 72, serves to prevent entrance of abrading material into ball bearings 70 and 71. A gear box 75, projecting downwardly from the body of case member 68, is provided with a cover plate 76 which is held in position by suitable screws. A worm gear 77, snugly slidable on sleeve 72, is keyed thereto to prevent rotation on the sleeve. The lower end of sleeve 72 is threaded to fit a threaded sleeve 78 which passes through cover plate 76 with slight clearance for turning. Any desired amount of preloading on ball bearings 70 and 71 may be had by tightening or backing off threaded sleeve 78. A worm 79 (Fig. 1) meshes with worm gear 77 and causes sleeve 72 to rotate when shaft 80, whereon worm gear 79 is mounted, is power actuated as described herein-after.

It will be understood from the description of my device thus far that, when the central bore in cage member 68 stands in a vertical position and upper oscillating member 49 is also vertical, then sleeves (or hollow spindles) 55 and 72 will be in exact alignment and a rod, exactly fitting each of these bores, may be pushed through both of these sleeves simultaneously. This is the ultimate and final test of the accuracy of construction and assembly of my device.

My mechanism, as thus far described, provides freedom for rotation of upper (convex) tool 63 and lower (concave) tool 73; moreover, cage member 68 is free to oscillate about the axis of hinge pins 7 and 8, and upper oscillating member 49 is free to oscillate about the axis of its hinge pins 48 and 51: the axis of rotation of each spindle intersects, at right angles, the axis whereon it oscillates: the axes of oscillation lie in a common plane and intersect at right angles. The mechanism for controlling and actuating the rotative and oscillatory movements of these parts will now be described.

Attached to the upper finished surface of cross 78 one tool and the work spindle carried in either of

member 4 at the right side of the machine by screws 81 (Fig. 3) is bearing bracket 82 which serves a dual function; first, it journals the crank shaft for oscillating the cage; second, it supports the main gear box. Bearing bracket 82 has an integral end flange 83 (Fig. 9) from the finished face of which projects annular boss 84 having a finished bore wherein is press fitted flanged bearing bushing 85. The outside surface of annular boss 84 is turned concentric with bearing 85. Gear box 86 contains a bore which fits with slight clearance over annular boss 84 and seats on a finished surface against end flange 83 on bearing bracket 82 and is held in position thereon by three screws 87 (Figs. 8 and 9) and by two through dowel screws 88. Crank shaft 89 is journaled, near one end, in flanged bearing bushing 85 and has press fitted on this end spur gear 90 which is suitably keyed and retained in position by nut 91. Meshing with spur gear 90 is gear 92 which, in turn, meshes with gear 93 fixed on main drive shaft 94, the latter being journaled in a flanged bearing bushing pressed in gear box cover 126 and in a flanged bearing bushing pressed in a bore in the back of gear box 86. Gear 92, serving as an idler between gears 90 and 93, rotates on stud 95 which is fixed in the free end of arm 96, the latter being mounted so that it may swing around the axis of main drive shaft 94. A clearance bore 97 in gear box 86, through which stud 95 passes is large enough to permit meshing of the driving gears if a gear somewhat larger or smaller in diameter than gear 90 is used to vary the cyclic pattern of the abrading movements as is hereinafter fully explained. A hardened steel washer 98 and a nut 99 serve to lock stud 95 in position after proper meshing relation has been established between gears 90 and 92. Main drive shaft 94 has fixed on its outboard end the pulley 100 and its other end 101, projecting through the rear wall of gear box 86 (Fig. 1), serves as a connection to drive, through flexible shaft 102, the worm shaft 66 (Fig. 7) for the purpose of rotating convex tool 63.

Power to rotate concave tool 73 is applied in the following manner: A helical gear 103 (Figs. 8 and 9), press fitted on and keyed to main drive shaft 94 meshes with helical gear 104, of somewhat smaller diameter, which is press fitted on shaft 105, the latter being journaled at one end in a bearing bushing 106 press fitted in gear box 86 and at the other end in a bearing bushing fitted into bearing plate 107 which is retained in position on gear box 86 by screws 108. The end of shaft 105, projecting through bearing plate 107 (Figs. 2 and 8), serves as a connection to drive, through flexible shaft 109, the worm shaft 80 (Fig. 1) for the purpose of rotating concave tool 73. To provide convenient means whereby the rotation of concave tool 73 may be reversed with respect to the rotation of convex tool 63, I have installed a second shaft 110, identical with shaft 105 and journaled in like manner, and having press fitted thereon helical gear 111 like helical gear 104 in all respects, except of opposite hand; and being arranged to mesh with gear 104 and to be driven thereby. By simply transferring flexible shaft 109 from the end of shaft 105 to the end of shaft 110, concave tool 73 will be rotated at the same speed but in the opposite direction.

It is of interest to note here that main drive shaft 94 and the shafts 105 and 110 control the rotation of both tools and, if gear 92 (Fig. 8) is rocked out of mesh with gear 90, both tools, or

the sleeves 55 or 72, may be rotated by motor drive without actuating, with respect to oscillation, either the upper oscillating member 49 or the cage member 68. This facility is of particular advantage when inspecting the work, prior to removal from the machine, after tilting bracket 9 has been rocked up into non-operating position.

Power to oscillate cage member 68 and the work or tool carried thereon is applied in the following manner: Crank shaft 89, journaled at one end in bearing 85 (Fig. 9) as hereinbefore described, is journaled near its other end in flanged bearing bushing 112 (Fig. 3) which is press fitted in the opposite end of bearing bracket 82. This end of crank shaft 89 carries securely fixed thereon crank disc 113 which is V-grooved on one side to fit against a beveled side of crank pin supporting block 114 and is square notched directly opposite to abut against the square side of clamping plate 115, the latter being beveled along its opposite side to contact the opposite beveled side of crank pin supporting block 114. Two screws 116, passing through clamping plate 115 and threaded into crank disc 113, serve to lock crank pin supporting block 114 into such position of eccentricity with respect to crank shaft 89 as is required to give any desired crank throw from zero to the full radius of the crank disc. Crank pin 117, fixed securely in crank pin supporting block 114, rotates freely in a bearing in the crank end of connecting rod 118. The opposite end of connecting rod 118 is forked, and a bearing in each forked end is a free turning fit on connecting rod screws 119 (Fig. 4) which are screwed securely into bosses 120 and 121 integral with cage supporting members 16 and 17 respectively. Driving power applied to crank shaft 89, through the gear train hereinbefore described (Fig. 9) will cause cage member 68 to oscillate at whatever amplitude, within the range of adjustability, the crank pin supporting block is set to provide.

Mechanism to operate upper oscillating member 49, to be effective and convenient in operation, must permit tilting bracket 9 to be shifted into operating and non-operating position freely and without disconnecting any mechanical parts or unmeshing and remeshing any elements of the gear train. The following means, beginning at gear 90 (Figs. 8 and 9), has been devised for performing this function: A spur gear 122, a duplicate of gear 92, rotates on stud 123 which is fixed in the swingable end of arm 124, the latter being mounted so that it may swing around the axis of shaft 125. Shaft 125 is journaled at one end in a bearing press fitted into gear box cover 126 (Fig. 9) and at the other end in a bearing press fitted in a bore in the rear wall of gear box 86. A spur gear 121, a duplicate of gear 93, is fixed on shaft 125 and meshes with gear 122, the latter acting as an idler between gears 90 and 127. The structures here are a duplication of the structures described hereinbefore in connection with gears 90, 92, and 93 and serve the same purpose; namely, to allow replacement of gear 90 by a gear somewhat larger or smaller in diameter to vary the motion pattern between the abrading members. Fixed on shaft 125 is helical gear 128 which meshes with helical gear 129 fixed on shaft 130. Shaft 130 is journaled in the upper part of main gear box 86 in bearings pressed into opposite side walls of this gear box (Fig. 8).

Shaft 130 (Figs. 2 and 3) extends from main gear box 86 into gear box 34 which is fitted upon the end of gear box 24 (Fig. 4) as hereinbefore described. Shaft 130 is suitably journaled in bear-

ings (not shown) pressed in opposite walls of gear box 34, and fast mounted on shaft 130, within gear box 34, is helical gear 131. Gear 131 meshes with helical gear 132 which is press fitted on one end of sleeve 133, and on the opposite end thereof is press fitted helical gear 134. Pressed into each end of sleeve 133 is a flanged bearing bushing 135 and these bushings are reamed to a free running fit on end portion 25 of hinge pin 8. The flanges 10 on these bushings, bearing at one end against the shoulder on hinge pin 8 and at the other end against the inner wall of gear box 34, take the end thrust from helical gears 132 and 134 which preferably, are of the same hand to minimize end thrust. In alignment with helical gear 134 in gear box 24, and meshing therewith is helical gear 136 in gear box 34 (Figs. 5 and 6). Gear 136 is a free running fit on stud 137 which is threaded and screwed into a tapped hole in end wall 23 of gear box 24. Gear 136 has press fitted therein a flanged bearing bushing which is arranged to take the end thrust of this helical gear.

Within lower part 29 of gear box 27 in alignment with gear 136 and meshing therewith is helical gear 138 which is fast mounted on shaft 139. Shaft 139 is journaled at one end in flanged bearing bushing 140 press fitted in a recess in the end of supporting pin 22, and at the other end in flanged bearing bushing 141 pressed into a recess in bearing support 142, the latter having a cylindrical surface turned to a good fit in the bore in lower part 29 of gear box 27 and being held in position therein by screws passing through its flanged end and entering tapped holes in the gear box. Also fast mounted on shaft 139 is helical gear 143, identical with gear 138, and gear 143 meshes with helical gear 144 which is fast mounted on crank shaft 145. Crank shaft 145 is journaled at one end in bearing bushing 146 pressed into a recess in gear box cover 147, the latter being secured to gear box 27 by suitable screws. Within a bore in the rear wall of gear box 27 in alignment with bearing bushing 146, are press fitted two flanged bearing bushings 148 wherein is journaled crank shaft 145. A crank disc 149, fixed on the end of crank shaft 145 and bearing against the flange of one bushing 148, and gear 144, bearing against the flange on the other bushing 148, take up the end thrust of helical gear 144 in either direction. Crank disc 149, identical with crank disc 113, carries the same kind of adjustable crank pin mechanism as hereinbefore described, and to this crank pin is attached connecting rod 150. This connecting rod (Figs. 1, 3, and 7) is also forked at one end and each forked end is provided with a bearing which is a good turning fit on connecting rod screws 151 (Fig. 7) which are screwed firmly into tapped holes in bosses located diametrically opposite each other on the upper part of upper oscillating member 49.

This mechanism for actuating upper oscillating member 49, provides complete freedom of movement of tilting bracket 9 and all mechanism attached thereto which must swing about the axis of hinge pins 7 and 8 whenever upper spindle 82 is to be removed from the machine or the work on the spindle is to be examined critically.

Basic principle of abrading action

It will be evident, after reading the foregoing detailed description of this device, that, over the working area of the tool and over the area of the work whereon a spherical surface is being generated, the abrading action is determined by the

composite motion pattern resulting from the combination of four primary movements of which the work and the tool each perform two. Mechanism has been hereinbefore described which actuates rotatively both the tool and the work in the same or in opposite directions and at slightly different rates, the exact difference in rate being determined by the relative diameters of gears 103 and 104. If both tool and work are rotating in the same direction, then the one of these which is mounted on the cage member will rotate slightly faster than the other which is supported from the upper oscillating member. Operating with this driving arrangement the absolute difference in rotation between the abrading elements is slight: it amounts only to the slight creep per revolution by which the cage mounted part advances ahead of the part carried by the upper oscillating member. Operating with the drives arranged to rotate tool and work in opposite directions, the absolute difference in rotation of these parts is multiplied several times; the creep between abrading members in this case, serving primarily to break up the motion pattern.

The mechanism described provides for oscillation of the upper oscillating member and of the cage, in planes at right angles and at slightly different frequencies. The frequency difference is determined, of course, by the relative rates of rotation of the two cranks which drive the oscillating members. The gear ratios in the upper oscillating member gear train are such that shaft 130 (Figs. 2 and 9) rotates exactly four times as fast as crank disc 149. Gears 128 and 129 (Fig. 8) are the same size and, inasmuch as gear 122 is only an idler, the ratio of gears 90 and 127, together with the four to one ratio above noted, determines the difference in rotative rate between crank discs 113 and 149. In this machine, as originally designed, gear 127 has 23 teeth and gear 90 has 89 teeth. If gear 90 had 92 teeth the ratio of gear 90 to gear 127 would be 92/23 or 4 to 1, then both crank discs would rotate in synchronism and there would be no frequency difference. By using gears of 23 teeth and 89 teeth (both prime numbers) these gears do not return to the exact same meshing position till the smaller gear has made 89 revolutions. During this period upper crank disc 149 has made 89/4 or 22 1/4 revolutions and crank disc 113 has made 23 revolutions. With these gear ratios the cranks cannot possibly return to the exact same relative positions till upper crank disc 149 has made 89 revolutions. This factor multiplied by the factor relating to relative rotation of tool and work gives a very long period for the cycle of the composite motion pattern. As hereinbefore indicated, provision is made in the mechanism for substituting gears having from one to four teeth more (or less) than gear 90 and by making such substitution the motion pattern cycle may be varied over a wide range.

Inasmuch as this machine provides for rotation of each abrading member by independent power drive and for oscillation of each abrading member in planes at right angles by independently adjustable power drives it is obvious that, with respect to the action at the abrading surfaces, this device produces substantially the same conditions as my former concentric rotatable universal joint mechanism hereinbefore referred to. This mechanism will, therefore, do substantially

the same sort of spherical surface generating work as is done by my former machine.

Operation of device

5 The first thing to be done in using my device is to mount concave and convex tools, which have been previously machined to the desired radius of curvature, in the machine. The concave tool 13 (Fig. 7) is securely seated in spindle 12 and 10 cage member 68 is elevated or lowered, as the case may require, by sliding along rods 67 until the concave surface of the tool is centered at the point of intersection of the axes of hinge pins 7 and 8 and hinge pins 48 and 51. The exact 15 position for the cage member 68 is determined by the use of a pin gage of the proper length centered in and seated against the flanged head 57 of upper sleeve 55 and bearing, at its lower end, against the surface of tool 13. With the 20 lower tool thus correctly positioned the upper oscillating member 49 (Fig. 4) is tilted back into inoperative position and upper spindle 62 with tool 63 mounted thereon is inserted in upper sleeve 55 and pushed all the way in till key pin 25 64 locks the spindle in place. The upper oscillating member is then rocked back into operative position; the upper end of spindle 62 projecting above the upper oscillating member is grasped by one hand; key pin 64 is withdrawn and tool 30 63 is seated gently against tool 13. The throw of each crank, one on crank disc 113 and the other on crank disc 149, is adjusted to make the 35 amplitude of each oscillating member the same when the amplitudes are measured at the abrading surface of the concave tool 13. The actual amplitude is determined, of course, by the diameter of the work to be surfaced.

The machine is now ready for grinding in the tools. The upper tool 63 is elevated, abrading material is applied to the concave surface of the lower tool and the upper tool is dropped back on the lower tool. Power is applied through pulley 100 to operate the machine which is allowed to run till the abrading material is worn out. 40 New abrading material is added as required, and additional water may be applied by using an atomizer while the machine is in operation. More pressure between the tools may be had by loading, by weights or preferably by spring mechanism, 45 the upper end of spindle 62 where it projects above upper oscillating member 49. The tools are ground together with progressively finer abrading materials till, when run together after being wiped free of abrading material, each tool shows 50 all over contact with the other; i. e., until no clouds are apparent on the surface of either tool.

To grind convex work, the upper tool spindle is removed from the machine and a work spindle carrying the work, is inserted in its place. The 55 procedure for roughing and fine grinding convex work is the same as previously described for grinding the tools. To grind concave work the procedure is as follows: The concave tool is left in the machine after it has been ground to exact curvature against the upper tool. The upper tool is dropped down into contact with the concave tool and a stop, slidable on the upper end of tool spindle 62, is pressed against the upper end of sleeve 61 and is locked in that position on spindle 62. This arrangement makes it possible to elevate the upper spindle to its highest position where it will be locked automatically by key pin 64, which operation will permit removal 60 of the concave tool and insertion of a chuck 65 whereon the work to be concave ground is mount- 70 75

ed. The convex tool may then be released and lowered into grinding contact with the work. The upper tool will continue to grind the work, if abrading material is added, until the tool descending into the work surface can go no further because of the stop on spindle 62 having contacted the upper end of sleeve 61. At this position the tool surface is oscillating on the exact radius at which it was ground originally against the bottom tool and hence it will generate the concave spherical surface of the correct radius on the work.

When polishing concave surfaces the upper tool spindle 62 is removed and a spindle carrying a pitch polisher mounted on its lower end is inserted in sleeve 55. The polisher, fed to the concave work by gravity or spring means, as previously mentioned in connection with tool grinding, may be formed when warm against the concave surface of the work. After the polisher has cooled, it will generate a true concave spherical surface on the work of substantially the same radius to which the work has been fine ground.

The procedure for polishing convex surfaces has been established in connection with my former spherical generator, and mechanism substantially the same as described in my Letters Patent of the United States No. 1,827,748, is used with the present spherical surface generator. After fine grinding of a convex spherical surface has been completed, the stop on the top of spindle 62 is set against the top of sleeve 61, as previously described in connection with setting the radius of oscillation of the convex tool for grinding concave work surfaces. By thus establishing the radius of oscillation at which the convex work surface has been fine ground, it is possible to raise the work spindle, remove the concave tool from lower sleeve 72 and substitute a pitch polishing tool. When the work spindle is dropped to the lowest position determined by the set stop the surface of the work will be at the exact same radius from the center of oscillation of the mechanism as it was when it was fine ground. The work spindle is then locked in this position and the pitch polisher, fed upward against the convex work surface under suitable spring tension provides sufficient pressure to rouge polish the work surface.

As is the case with my former lens generating machines, this device, performing those motions required by the geometry of the surface, not only generates a spherical surface on the work but also continually regenerates a mating spherical surface on the tool. In other words, any two pieces of material, whatever their initial shape, if ground together in this machine with abrading material between them and ground together long enough, each of these pieces of material will have generated upon it by the other a true spherical surface exactly mating the other. In a true generating machine the work takes its surface form from the movements it makes with respect to the tool, rather than from the surface shape of the tool, and the surface of the tool, if initially not correct in form or not true to the axes of the machine, will be regenerated automatically to correct form and true to the control axes of the machine.

The essential difference in the present device, compared to my former mechanism, resides in the means for rotating the work and tool. In the former mechanism both of the oscillating structures are also rotated and within each oscillating structure the work (or tool) is either fixed or

keyed to prevent rotation therein. Because the oscillating structures were formerly rotated, it was essential that they be suspended from universal joints and the rotation of the structures was accomplished through rotating these universal joints. In the present device, hollow spindles within the oscillating members are rotated through flexible shaft drives and substantially equivalent abrading conditions are obtained without requiring rotation of the oscillating structures.

This arrangement greatly simplifies the structures, renders the construction more open and get-at-able so that much shorter radius curves may be handled, and permits use of one gimbal ring by means of which the upper oscillating member may be rocked out of operating position without, in the least degree, disturbing the accuracy of centering or the radius of oscillation of either the work or the tool. This latter feature of the present device is most important because; first, it permits critical inspection of the work at all stages of grinding and during polishing without requiring removal of the work from the machine; and second, it allows transfer of the work and spindle whereon the work is mounted from machine to machine for progressive grinding and for polishing. This facility makes it practical and economical to arrange machines in groups or batteries, each individual machine being equipped with tools and operating with abrading material for a particular grain of grinding from the coarsest roughing to the finest fine grind, also with polishing tools, pitch coated, and operating with rouge for the finest known polishing. The work, mounted on a spindle, is transferred from machine to machine by simply transferring the spindle after the operation in one machine is completed. This arrangement saves the time required to change over and clean up the machine between operations when all grades of grinding and the polishing operation are carried out on one machine. It also practically eliminates the danger of contaminating the work with a coarser grade of abrading material when changing to progressively finer abrading, thereby avoiding one of the major sources of scratches, an ever present danger in lens manufacture. In operating the present device in batteries, each machine does only one grade of abrading and only the work, as it advances from machine to machine, requires thorough and careful washing and cleaning to avoid scratches on the finished surface.

The mechanism, as hereinbefore described, is set up to produce true spherical surfaces; i. e., all movements, both rotative and oscillatory, take place around the center of curvature of the abrading surface generated upon the tool by the operation of the machine. In other words, the setup thus far described conforms to the geometry of a spherical surface. Certain types of high grade photographic lenses can be improved in performance characteristics if a surface on one or more elements is made very slightly aspheric. This fact has been known and generally recognized by optical designers for years but there has been no satisfactory means available for producing such surfaces, even in limited quantities. With my present device there are several ways of generating aspheric surfaces which may be duplicated exactly in any desired quantity. Duplication of aspheric surfaces is possible because the mechanism will, of itself, ultimately produce

that stabilized form of aspheric surface on the tools for which it is adjusted regardless of the initial surface contour of the tools when put on the machine.

Considered geometrically, there are two ways of decentering my mechanism, any one or both of which would produce aspheric surfaces; first, vertical displacement of one axis of oscillation; second, lateral displacement of either or both oscillating members with respect to the common vertical axis of the spindles. Each combination of the various possible decentrations will produce a different aspheric surface pattern but in all cases each surface will be symmetrical about its principal axis; i.e., it will be a surface of revolution. Mechanically, the decentration may be brought about by substituting in the mechanism other tilting brackets ⁹ wherein the hinge pin axes lie in slightly spaced parallel planes, and/or wherein one of the axes of oscillation is not positioned symmetrically with respect to the centering faces of the bosses wherein the other pair of hinge pins are supported. This deliberate misalignment and decentering of the axes of oscillation is illustrated in Fig. 10 wherein the aligned bores on axis A—A are equivalent to the bores wherein ball bearings ⁴⁷ and ⁵⁰ are mounted as shown in Fig. 7. In Fig. 10, the vertical axis B—B is drawn midway between the faces of bosses ⁴⁵ and ⁴⁶. The bore ⁷, wherein hinge pin ¹ is press fitted, is disposed at right angles to axis A—A; it is centered on axis B—B but is offset vertically from axis A—A by an amount ^a. The hinge pin bore ^{7'}, shown in broken line, on the other hand, is centered on axis A—A but offset radially from axis B—B by an amount ^b. Hinge pin bore ^{7''}, shown in broken line, combines vertical offset ^c and radial offset ^d. The offsets ^a, ^b, ^c and ^d shown in Fig. 10 are greatly magnified so the principle may be illustrated in the drawings. In practical cases, these offsets would not ordinarily exceed a few thousandths of an inch. Lateral decentration in this device may also be produced by inserting various spacer washers to offset an oscillating member.

While I have described particular structures for performing the various movements required of a spherical surface generating mechanism, which structures also provide certain new facilities and utilities not possessed by my former device, it is recognized that other usable structures capable of performing the same functions may occur to those skilled in the art, particularly after observing the performance of my present mechanism. The claims forming a part of this application and hereunto attached are drawn with sufficient scope to cover any and all mechanisms of the character described which possess the mechanical freedom of movement and adjustability to perform fully the functions which my device is intended to perform.

Having thus fully described my device, what I claim is:

1. A surface generating device comprising a frame structure, an upper oscillating member hingedly supported on said frame structure, a sleeve rotatably supported within said upper oscillating member, a work spindle slidable within said sleeve but keyed to rotate therewith, a cage member hingedly supported on said frame structure, a second sleeve rotatably supported within said cage member, a tool mounted on said second sleeve, and means adapted and arranged to oscillate said upper oscillating member and said cage member about their respective hinge sup-

ports while rotating said sleeves and the work spindle and tool carried thereby.

2. A spherical surface generating device comprising a frame structure, an upper oscillating member hingedly supported on said frame structure, a sleeve rotatably supported within said upper oscillating member, a tool spindle slidable within said sleeve but keyed to rotate therewith, a cage member hingedly supported on said frame structure, a second sleeve rotatably supported within said cage member, a work supporting chuck mounted on said second sleeve, and means adapted and arranged to oscillate the hingedly supported members while rotating positively said sleeves.

3. A surface generating device comprising a frame structure, a pair of aligned hinge pins supported in the upper portion of said frame structure, an upper oscillating member carried on said hinge pins, a sleeve rotatably supported within said oscillating member, the axis of said sleeve intersecting the axis of said hinge pins at right angles, work supporting means controlled by said sleeve, a second pair of aligned hinge pins supported in said frame structure, the axis of said second pair of hinge pins lying in the same plane as the axis of said first-mentioned pair of hinge pins and intersecting the same at right angles, a cage member carried on said second pair of hinge pins, a second sleeve rotatably supported within said cage member, the axis of said second sleeve intersecting the axis of said second pair of hinge pins at right angles, a tool carried on said second sleeve, means for oscillating simultaneously the hinge pin supported members, and means for rotating said sleeves.

4. A spherical surface generating device comprising a frame structure, a pair of aligned hinge pins supported in the upper portion of said frame structure, an upper oscillating member carried on said hinge pins, a sleeve rotatably supported within said oscillating member, work supporting means controlled by said sleeve, a second pair of aligned hinge pins supported in said frame structure, the axis of said second pair of hinge pins lying in the same plane as the axis of said first-mentioned pair of hinge pins and intersecting the same at right angles, a cage member carried on said second pair of hinge pins, a second sleeve rotatably supported within said cage member, a tool carried on said second sleeve, the axis of each of said sleeves standing at right angles to the axis of its respective hinge pins at the point where the hinge pin axes intersect at right angles, means for oscillating simultaneously the hinge pin supported members, and means for rotating said sleeves.

5. In a surface generating device, a frame structure, a pair of aligned hinge pins supported in the upper portion of said frame structure, an upper oscillating member carried on said hinge pins, a sleeve rotatably supported within said oscillating member, a second pair of aligned hinge pins supported in said frame structure, the axis of said second pair of hinge pins lying in the same plane as the axis of said first-mentioned pair of hinge pins and intersecting the same at right angles, a cage member carried on said second pair of hinge pins, a second sleeve rotatably supported within said cage member, the axis of each of said sleeves standing at right angles to the axis of its respective hinge pins and displaced somewhat from the point where the hinge pin axes intersect at right angles, means for oscillating the hinge pin supported members, and means for rotating said sleeve.

6. A surface generating device comprising a frame structure, a pair of aligned hinge pins supported in the upper portion of said frame structure, an upper oscillating member carried on said hinge pins, a sleeve rotatably supported within said oscillating member, work supporting means controlled by said sleeve, a second pair of aligned hinge pins supported in said frame structure, the axis of said second pair of hinge pins being disposed at right angles to the axis of said first-mentioned pair of hinge pins, a cage member carried on said second pair of hinge pins, a second sleeve rotatably supported within said cage member, a tool carried on said second sleeve, the axis of each of said sleeves standing at right angles to the axis of its respective hinge pins, means for oscillating the hinge pin supported members, and means for rotating said sleeves.

7. In a surface generating device, a frame structure, a pair of aligned hinge pins supported in the upper portion of said frame structure, an upper oscillating member carried on said hinge pins, a sleeve rotatably supported within said oscillating member, a second pair of aligned hinge pins supported in said frame structure, the axes of said first-mentioned pair and said second pair of hinge pins lying in different planes, a cage member carried on said second pair of hinge pins, a second sleeve rotatably supported within said cage member, the axis of each of said sleeves standing at right angles to the axis of its respective hinge pins, means for oscillating the hinge pin supported members, and means for rotating said sleeves.

8. A surface generating device comprising a supporting frame structure, a pair of aligned hinge pins mounted in the upper portion of said frame structure, a tilting bracket containing end bores wherein said hinge pins are press fitted and aligned cross bores positioned symmetrically at right angles to the axis of said end bores, a second pair of hinge pins mounted in said cross bores, an upper oscillating member carried on said second pair of hinge pins, a sleeve rotatably mounted within said upper oscillating member, work supporting means controlled by said sleeve, cage supporting members hingedly mounted on said first-mentioned pair of hinge pins between said tilting bracket and said frame structure, a cage member carried from said cage supporting members, a second sleeve rotatably mounted within said cage member, a tool carried on said second sleeve, means attached to said tilting bracket adapted and arranged to swing said tilting bracket on said first-mentioned pair of hinge pins and lock same either in operating or work inspection position, means for rotating said sleeves, and means for oscillating simultaneously said upper oscillating member and said cage members.

9. A spherical surface generating device comprising a supporting frame structure, a pair of aligned hinge pins mounted in the upper portion of said frame structure, a tilting bracket containing end bores wherein said hinge pins are press fitted and aligned cross bores positioned symmetrically at right angles to the axis of said end bores, the axes of said cross bores and the axes of said end bores lying in a common plane, a second pair of hinge pins mounted in said cross bores, an upper oscillating member carried on said second pair of hinge pins, a sleeve rotatably mounted within said upper oscillating member, work supporting means controlled by said sleeve, cage supporting members hingedly mounted on said first-mentioned pair of hinge pins between

said tilting bracket and said frame structure, a cage member carried adjustably from said cage supporting members, a second sleeve rotatably mounted within said cage member, a tool carried on said second sleeve, said upper oscillating member and said cage member being so organized and positioned within said supporting frame structure that the axis of said first-mentioned sleeve and the axis of said second sleeve are in exact alignment when said sleeves stand vertically, means attached to said tilting bracket adapted and arranged to swing said tilting bracket on said first-mentioned pair of hinge pins and lock same either in operating or work inspection position, means for rotating said sleeves, and means for oscillating simultaneously said upper oscillating member and said cage member.

10. In a device of the character specified, a supporting frame structure, a tilting bracket hingedly supported in the upper portion of said frame structure, an upper oscillating member hingedly supported in said tilting bracket at right angles to the hinge support of said tilting bracket, a gear box structure attached to said tilting bracket, a crank shaft journaled in said gear box structure, adjustable crank mechanism fixed on said crank shaft, a connecting rod joining said crank mechanism to said upper oscillating member, a gear train within said gear box structure, and means associated with said gear box structure adapted and arranged to swing said tilting bracket and connected mechanism and lock same either in a vertical or oblique position, said gear train being adapted and arranged to oscillate said upper oscillating member and also to allow freedom for swinging said tilting bracket.

11. In a device of the character specified, a supporting frame structure, a pair of aligned hinge pins rotatably mounted in said frame structure, a tilting bracket wherein said hinge pins are press fitted, an upper oscillating member hingedly supported in said tilting bracket, a cage member swingably supported on said hinge pins, means adapted and arranged to swing said tilting bracket and lock same either in operating or work inspecting position, adjustable crank mechanisms and enclosed gear trains carried on said supporting structure adapted and arranged to oscillate said upper oscillating member and said cage member in planes at right angles at different frequencies.

12. In a device of the character specified, a supporting frame structure, a tilting bracket hingedly supported on said frame structure, an upper oscillating member hingedly supported in said tilting bracket, a sleeve rotatably mounted within said upper oscillating member, a cage member hingedly supported in said frame structure, a second sleeve rotatably mounted within said cage member, means adapted and arranged to swing said tilting bracket and lock same in a vertical or oblique position, adjustable right angle drive crank mechanisms and their enclosed operating gear trains carried on said supporting frame structure and adapted and arranged to oscillate said upper oscillating member and said cage member in planes at right angles at different frequencies, and means for rotating said sleeves.

13. In a device of the character specified, a supporting frame structure, a cage member, and a tilting bracket hingedly supported in said frame structure on common hinge pins, an upper oscillating member hingedly supported in said tilting bracket, a sleeve rotatably mounted in said upper oscillating member, a work spindle slidable with-

in said sleeve, a tool mounted on said cage member, and means associated with said tilting bracket adapted and arranged to swing said tilting bracket and lock same in two positions; the first position allowing operative engagement of work carried on said work spindle with said tool mounted on said cage member, the second position disengaging said work from said tool and permitting withdrawal of said work spindle from said upper oscillating member.

14. In a spherical surface generating device, a pair of hollow spindles rotatably mounted, a work spindle slidably mounted within one of said hollow spindles, a tool fixed on one end of the other of said hollow spindles, hingedly mounted means whereby said hollow spindles are supported so they may be oscillated in planes at right angles, a supporting frame structure for said hingedly mounted means, means adapted and arranged to oscillate said hollow spindles at different frequencies, and means for rotating said hollow spindles at different rates.

15. In a spherical surface generating device, a pair of sleeves rotatably mounted, hingedly mounted means whereby said sleeves are supported so they may be oscillated in planes at right angles, a supporting frame structure for said hingedly mounted means, means whereby one of said sleeves may be tilted in the plane of oscillation of the other of said sleeves, gear driven crank means for oscillating said sleeves adapted and arranged to allow tilting of one sleeve in the plane of oscillation of the other, and means for rotating said sleeves while they are being oscillated.

16. In a spherical surface generating device, a pair of hollow spindles rotatably mounted, a work spindle slidably mounted within one of said hollow spindles, a tool fixed on one end of the other of said hollow spindles, hingedly mounted means whereby said hollow spindles are supported so they may be oscillated in different planes, a supporting frame structure for said hingedly mounted means, means adapted and arranged to oscillate said hollow spindles at different relative frequencies, means for changing the relative frequencies by small increments, and means for rotating said hollow spindles at different rates and in the same and in opposite directions.

17. In a device for generating spherical surfaces, a supporting frame structure, a pair of aligned hinge pins mounted with freedom to turn in said frame structure, a cage member supported swingably upon said hinge pins, a tilting bracket wherein said hinge pins are press fitted, an upper oscillating member hingedly supported within said tilting bracket and adapted and arranged to swing at right angles to said cage member, said tilting bracket being made swingable about the axis of said pair of aligned hinge pins so that said upper oscillating member may be tipped out of alignment with said cage member sufficiently to permit withdrawal of work for inspection and for finer grinding (or polishing) in a similar mechanism.

18. In a device for generating true spherical surfaces, a tilting bracket, a pair of aligned bores in said tilting bracket wherein a pair of hinge pins are press fitted, means including a base and upright brackets for hingedly supporting said hinge pins, an oscillating tool carrying member supported on said hinge pins, a second pair of aligned bores in said tilting bracket, and means supported in said second pair of aligned bores adapted and arranged to support hingedly an

oscillating work carrying member, the axes of said pairs of aligned bores intersecting at right angles.

19. In a device for generating specified aspheric surfaces, a tilting bracket, a pair of aligned bores in said tilting bracket wherein a pair of hinge pins are press fitted, means including a base and upright brackets for hingedly supporting said hinge pins, an oscillating tool carrying member supported on said hinge pins, a second pair of aligned bores in said tilting bracket, and means supported in said second pair of aligned bores adapted and arranged to support hingedly an oscillating work carrying member, the axes of said pairs of aligned bores being disposed at right angles to each other and lying in spaced parallel planes, the spacing between said parallel planes having a specified, not an accidental value, for the purpose of determining the precise nature and the exact degree of departure of the generated aspheric surface from a true sphere.

20. In a device for generating true spherical surfaces, a tilting bracket, a pair of aligned bores in said tilting bracket wherein a pair of hinge pins are press fitted, means including a base and upright brackets for hingedly supporting said hinge pins, an oscillating member supported on said hinge pins, a hollow spindle rotatably mounted within said oscillating member, a work spindle slidably supported within said hollow spindle, a second pair of aligned bores in said tilting bracket, a second oscillating member, means supported in said second pair of aligned bores adapted and arranged to support hingedly said second oscillating member, a second hollow spindle rotatably mounted within said second oscillating member, and a tool fixed on one end of said second hollow spindle, said pairs of aligned bores, oscillating members and hollow spindles being so organized that the axes of said aligned bores intersect at right angles and the axes of said hollow spindles pass through this intersection.

21. In a device for generating specified aspheric surfaces, a tilting bracket, a pair of aligned bores in said tilting bracket wherein a pair of hinge pins are press fitted, means including a base and upright brackets for hingedly supporting said hinge pins, an oscillating member supported on said hinge pins, a hollow spindle rotatably mounted within said oscillating member, a work spindle slidably supported within said hollow spindle, a second pair of aligned bores in said tilting bracket, a second oscillating member, means supported in said second pair of aligned bores adapted and arranged to support hingedly said second oscillating member, a second hollow spindle rotatably mounted within said second oscillating member, and a tool fixed at one end of said second hollow spindle, said pairs of aligned bores, oscillating members and hollow spindles being so organized that the axes of said aligned bores intersect at right angles and the axis of one of said hollow spindles clears this intersection by a specified exact amount, for the purpose of determining the precise nature and the exact degree of departure of the generated aspheric surface from a true sphere.

22. In a device for generating specified aspheric surfaces, a tilting bracket, a pair of aligned bores in said tilting bracket wherein a pair of hinge pins are press fitted, means including a base and upright brackets for hingedly supporting said hinge pins, an oscillating member supported on said hinge pins, a hollow spindle rotatably mounted within said oscillating member, a work spindle slidably supported within said hollow spindle, a

second pair of aligned bores in said tilting bracket, a second oscillating member, means supported in said second pair of aligned bores adapted and arranged to support hingedly said second oscillating member, a second hollow spindle rotatably mounted within said second oscillating member, and a tool fixed at one end of said second hollow spindle, said pairs of aligned bores, oscillating members and hollow spindles being so organized that the axes of said aligned bores intersect at right angles and the axis of each of said hollow spindles clears this intersection by a specified exact amount, for the purpose of determining the precise nature and the exact degree of departure of the generated aspheric surface from a true sphere.

23. In a device for generating specified aspheric surfaces, a tilting bracket, a pair of aligned bores in said tilting bracket wherein a pair of hinge pins are press fitted, means including a base and upright brackets for hingedly supporting said hinge

5 pins, an oscillating member supported on said hinge pins, a hollow spindle rotatably mounted within said oscillating member, a work spindle slidably mounted within said hollow spindle, a second pair of aligned bores in said tilting bracket, a second oscillating member, means supported in said second pair of aligned bores adapted and arranged to support hingedly said second oscillating member, a second hollow spindle rotatably mounted within said second oscillating member, and a tool fixed on one end of said second hollow spindle, said pairs of aligned bores, oscillating members and hollow spindles being so organized that the axes of said aligned bores are disposed at right angles to each other but lie in spaced parallel planes and the axis of each of said hollow spindles passes with specified clearance the respective axis whereon its oscillating member is hingedly supported.

ARTHUR J. HOLMAN.
